PORATION OF DELAWARE

COMBINED CLOTHES WASHER AND DRIER

Original application filed May 7, 1925, Serial No. 28,564. Divided and this application filed January 24,
1928. Serial No. 249,038.

This invention relates to a combined clothes washer and centrifugal drier involving the use of juxtaposed upright containers mounted upon a single supporting frame and containing the washing and drying mechanisms respectively adapted to be driven from the same source of power which is mounted upon the frame preferably in a plane directly beneath the containers.

10 This application is a division of our application on a Combined clothes washer and drier, filed May 7, 1925, Serial No. 28,564, now Patent 1,720,851, granted July 16, 1929.

15 The main object of our invention is to provide a centrifugal clothes drier, the operation of which may be controlled from a single point.

Another object is to provide a drier of this type in which the cover will be locked in 20 position when the operating handle has been adjusted to cause the operation of the device.

Another object is to provide a mechanical means whereby the movement of the drier will be stopped when the operating power 25 has been disconnected.

Other objects and advantages relate to the size, shape and arrangement of parts, all as will more fully appear from the following description, taken in connection with the accompanying drawings in which:—

Figure 1 is a top plan of a combined clothes washer and centrifugal drier embodying the various features of the invention except that the cover for the washing vat is removed to 35 show the interior washing mechanism, a portion of a laundry tray being also shown directly under the outer edge of the drain board of the drier.

Figure 2 is an enlarged transverse vertical sectional view, partly broken away, taken on line 2—2, Figure 1.

Figure 3 is an enlarged detail sectional view taken on line 3—3, Figure 1.

Figure 4 is an enlarged vertical sectional view, partly broken away taken on line 4—4, Figure 1, the laundry tray being omitted.

Figure 5 is an enlarged detail sectional view taken in the plane of line 5—5, Figure 4.

Figure 6 is a horizontal sectional view taken in the plane of line 6—6, Figure 4,

mainly in a plane below the containers for the washing and drying mechanisms but showing in addition the full tripod construction of the frame, the motor and the conduits for the circulation of the washing fluid from one container to the other and the discharge nozzle leading to the exterior of the machine.

Figure 7 is an enlarged vertical sectional view taken in the plane of line 7—7, Figure 6.

Figure 8 is an enlarged transverse sectional view of the pump taken in the plane of line 8—8, Figure 6.

Figure 9 is an enlarged top plan of the cap for the revoluble clothes container of the centrifugal drier.

Figure 10 is an enlarged detail sectional view taken on line 10—10, Figure 1.

Figure 11 is an enlarged vertical sectional view taken on line 11—11, Figure 1.

Figures 12 and 13 are enlarged detail sectional views taken respectively in the planes of lines 12—12 and 13—13, Figure 6.

As illustrated, this machine comprises a main supporting frame of the tripod type having a substantially horizontal platform 70 —1— carried by a plurality of, in this instance, three legs —2— which are arranged at the angles of an isosceles triangle and in addition to being secured to the platform —1— by bolts —3— are also connected to each other some distance below the platform by braces —4— and —4'— extending along the sides of the triangle and having their ends secured to the legs by bolts —5—.

The lower ends of the legs are provided 85 with castors —2'— adapted to rest upon the floor to permit the machine as a whole to be moved from place to place along the floor as may be more convenient for the operator as, for example, when using the machines in connection with stationary laundry trays in a 90 manner hereinafter described.

The platform —1— is of sufficient horizontal area within its marginal edge to receive and support a relatively large circular washing vat or tub —6— and a relatively small circular drier vat or tub —7— side by side in fixed relation to each other with the larger vat nearest the base of the triangle and the smaller vat nearer the apex of the 95 100

triangle and the axes of both vats in a vertical plane bisecting the angle at the apex of the triangle and thereby passing through the base of the triangle midway between the adjacent angles.

The vertical axes of the vats —6— and —7— are wholly within the triangle so that the angles at the base of the triangle will lie in vertical planes substantially coincident with the adjacent sides of the vat —6— and at equal distances from the axis thereof while the angle at the apex of the triangle will be in a vertical plane substantially coincident with the corresponding side of the periphery of the vat —7— and, therefore, the legs —2— which are secured to the angles of the triangular bracing frame may be substantially straight vertically and secured to the adjacent portions of the peripheries of the vats —6— and —7— and also to the adjacent portions of the perimeter of the platform —1— which follows closely the circular outlines of both vats.

The object of this triangular supporting and bracing means for the combined washer and drier is to bring all of the mechanisms to be brought into a unitary structure supported on the floor at three bearing points for stabilizing purposes and also to reduce to a minimum any vibration incidental to the joint or independent operation of both the washing and drying mechanism or either of said mechanisms separately, as will be hereinafter more fully explained, it being understood that the platform —1— serves as a rigid tie connection between the two vats —6— and —7— to hold them against relative movement and in differentiating the drying mechanism from the washing mechanism, it will be observed that the distinction is only nominal, the "washing mechanism" being employed to loosen the dirt and other foreign matter from the clothes by alternate pressure and suction while the centrifugal "drying mechanism" serves the double purpose of freeing the dirt and other foreign matter in solution from the clothes and also for drying the clothes so that the latter may reasonably be termed a supplemental washer as well as a dried.

Washing mechanism

In addition to the vat —6— the washing mechanism comprises a plurality of, in this instance, two inverted cup shaped dashers or cups —8— operatively connected to a yoke —9— which, in turn, is adjustably mounted on a vertically mounted plunger —10—, the latter being reciprocably movable in a suitable gland —11— in the bottom of the vat —6— co-axial therewith while the cups —8— are mounted upon the yoke —9— at one side of said axis for engagement with the clothes and washing fluid in the vat as the plunger —10— and cups are reciprocated vertically.

Any suitable means may be employed for imparting vertical reciprocatory motion and also rotary motion to the upright shaft or plunger —10—, said means being partially shown in the drawings as consisting of an electric motor —12— secured to the underside of the platform —1— and having its armature shaft —13— connected by a universal joint —14— to a co-axial shaft —15— which is journaled in a suitable gear case —16— on the underside of the platform —1—, said shafts —13— and —15— being located at one side of the axis of the vat —6— and parallel with a direct line between the axes of both of the vats —6— and —7—.

A pinion —17— is secured to the driving shaft —15— within the gear case —16— and meshes with a gear —18—, which is secured to the hub of a second pinion —19—, the latter being loosely mounted upon a counter shaft —20— so as to permit the gear and pinion to rotate relatively to said shaft for a purpose presently described.

The pinion —19— meshes with a relatively large gear —21— which is loosely mounted upon a crank shaft —22— for relative rotary movement and also has an independent axial movement into and out of clutching engagement with a clutch member —23— having an elongated hub journaled in a bearing —24— in the adjacent end of the gear case —16— and carrying at its outer end a crank arm —25—.

The hub of the clutch member —23— together with the crank arm —25— are keyed to each other and to the shaft —22— by means of a key or pin —26—, Figure 6, to cause those parts to rotate in unison.

The crank arm —25— is operatively connected in any well known manner to the intermediate portion of a rock arm or lever —27— extending radially to and at one side of the axis of the vat —6— below the platform —1— and having one end pivotally connected at —28— to the outer edge of the platform and its inner end suitably connected to the lower end of the plunger —10— whereby as the shaft —22— with the crank arm —25— thereon is rotated through the medium of the gear train and clutch previously described rocking motion will be imparted to the rock arm or lever —27— for reciprocating the plunger —10— and thereby effecting a corresponding reciprocatory movement of the yoke —9— and cups —8— carried thereby.

A coiled spring —29— may be connected in any well known manner to the lever —27— and to the frame of the machine for retracting the inner end of the lever and parts carried thereby upwardly and thereby assisting the motor in lifting those parts.

The counter shaft —20— is located between the axes of the vats —6— and —7— and approximately in a direct line between

said axes while the driving shaft —15— and crank shaft —22— are located at opposite sides of and parallel with the counter shaft —20— and, therefore, at opposite sides of the vertical axis of the vat —6— and plunger —10— while the motor —12— and gear case 16 containing the gear train connections between the driving shaft —15— and lever —27— are also located at opposite sides of the lever —27— and plunger —10— so that the load incidental to the operation of the cups —8— for washing purposes is nearly in the center of the power plant on the underside of the platform —1— for the purpose of distributing the power transmitting mechanism more evenly around the plunger and thereby introducing a more effective balance and consequent reduction of vibration in the operation of the washing mechanism.

As previously stated, the clutch gear —21— is movable axially into and out of clutching engagement with the clutch member —23— and for this purpose is provided with apertures —30— adapted to receive studs —31— on the member —23— when the two parts are brought together for transmitting motion from the pinion —19— to the crank shaft —22—.

The hub of the clutch gear —21— is provided with an annular groove —32— for receiving a shifting member —33— which is connected to one end of a shifting rod —34—, Figure 6, said split rod being mounted in a suitable bearing in the adjacent side of the gear case —16— and having its outer end connected to one end of a shifting lever —35—.

This lever —35— is pivoted at —36— to the gear case —16— and has its other end connected by a link —37— to a crank arm —38— on the lower end of an upright tubular shaft —39—, Figure 2.

The tubular upright shaft —39— extends upwardly along the outside of and in close proximity to the vat —7— and has its lower end journaled in a suitable bearing —40— on the platform —1— and its upper end provided with a hand lever —41— secured thereto for rocking said shaft about its axis and thereby transmitting axial motion to the clutch gear —21— through the medium of the link —37—, lever —35— and shifting rod —34— for engaging and disengaging said gear clutch with the clutch member —23—.

It is now evident that while the motor —12— is in operation positive motion will be transmitted to the gear clutch 21 and that if the hand lever —41— is shifted in one direction the clutch gear —21— will be forced into engagement for operating the crank shaft —22— and thereby reciprocating the plunger —10— with the cups —8— thereon for washing purposes while on the other hand if the hand lever —41— is shifted in the opposite

direction the clutch gear —21— will be withdrawn from engagement with the member —23— to be operated independently thereof to stop the reciprocation of the plunger and parts carried thereby.

70

Centrifugal drier

An upright cylindrical cage —42— is rotatably mounted within the vat —7— coaxial therewith but clear from the walls thereof to avoid friction therewith and comprises a perforated shell —43— having its lower end secured to a circular supporting plate or bottom —44— and its upper end provided with a concavo-convex lid —45— removably mounted thereon, but frictionally engaged therewith to be rotated thereby in a manner hereinafter described.

The counter shaft —20— is connected by a universal joint —46— to an axial extension shaft —20'— which is journaled in one side of a gear case —47— and is operatively connected by a beveled gear —48— and pinion —48'— to an upright shaft —50— which is journaled in a suitable gland —51— in the platform —1— coaxial with the axis of the cage —42— and has its opposite end provided with a hexagonal or other angular head —52— engaging in a similarly formed angular recess —53— in the bottom plate —44— for transmitting rotary motion from said upright shaft —50— to the cage —42— and permitting said cage to be removed from the head —52— by upward displacement when desired.

The gear case —47— is secured to the underside of the platform —1— as shown in Figure 4 and is provided in its lower side with an adjustable and thrust bearing screw —54— for the lower end of the upright shaft —50— and thereby to hold the rotary head —52— out of frictional engagement with the upper end of the gland —51— which is preferably of the stuffing box type to prevent leakage of water from the bottom of the vat —7— through the gland.

Suitable means is provided for controlling the operation of the centrifugal drier mechanism independently of the washing mechanism while the motor is in operation and, as previously stated, the gear —18—, which is driven continuously by the motor through the medium of the pinion —17—, is loosely mounted upon the shaft —20— to rotate independently thereof and is provided with a conical clutch face —55— adapted to be engaged by a conical clutch member —56— on one end of a brake drum —57— which is splined on the shaft —20— for axial movement and is spring-pressed in one direction by a coiled spring —58— for frictionally engaging the clutch member —56— with the clutch gear —18— for transmitting motion to said shaft —20— and thence through the shaft —20'— and gears —48— and —48'— to the upright

100

105

110

115

120

125

130

shaft —50— for rotating the cage —42—, the clutch member —56— being riveted or otherwise secured to the hub of the brake drum —57—, as shown in Figure 4.

5 The brake drum —57— is provided with an outwardly projecting annular flange having a friction washer —57'— of fibre or equivalent material adapted to be engaged by a brake shoe —59— constituting a part of the clutch shifting means.

10 An upright rock shaft is journalled in suitable bearings in the gear case —16—, Figure 6, and has its lower end provided with a crank arm —61— pivotally connected at —62— to the brake ring —59— and its upper end provided with a crank arm —63— connected by a link —64— to a crank arm —65— on the lower end of an upright rock shaft —66— which extends vertically through the tubular shaft —39— coaxial therewith and has its upper end journalled in the adjacent side of a frame —67— and is provided with a hand lever —68— by which it may be turned for shifting the clutch member —56— into and 15 out of clutching engagement with the clutch gear —18— and also for moving the brake ring —59— into and out of engagement with the friction face —57'— of the brake drum —57—.

20 The frame —67— embraces a portion of the periphery of the upper end of the washing vat —6— and may be rigidly secured thereto by brazing or other suitable fastening means and extends entirely around the upper end 25 of the drier vat —7— to which it may be also rigidly secured by brazing or otherwise to form a rigid tie between the upper ends of both vats for holding them in fixed relation, said frame being provided with a central cylindrical opening —69— of sufficiently 30 large diameter to permit the cage —42— to be withdrawn therethrough by upward displacement when desired or replaced by downward displacement into interlocking engagement with the driving head —52—.

35 A lid or cover —70— for the opening —69— is hinged at one side at —71— to the frame —67— at a point beyond the adjacent side of the vat —7— and when closed is adapted to engage the upper inner faces of the walls of the opening —69— to form a substantially water-tight joint therewith or it is held in place by a locking bolt —72— and spring —73—, both guided in a bushing 40 —74— in the adjacent side of the frame —67—, the outer end of the bolt being provided with a handle —75— by which it may be withdrawn from its locking position against the action of its retracting spring —73—, 45 Figure 3.

50 The lid —70— is also concavo-convex in cross section and is provided at the side nearest the locking bolt —72— with a handle —70'— by which it may be opened and closed.

55 The lever —68— which controls the opera-

tion of the centrifugal drier cage —42— is provided with an extension —68— movable into and out of engagement with the upper face of the adjacent side of the lid —70— for locking said lid in its closed position when the lever —68— is adjusted to cause the rotation of the cage —42— and to release said lid when the lever is adjusted to stop the operation of the cage, but the lid —70— cannot be raised until it is further unlocked by the withdrawal of the bolt —72— thereby reducing the liability of opening the lid while the cage with the clothes therein is being rotated, it being understood that when the lever —68— is adjusted to stop the rotation of the cage it will be necessary to withdraw the bolt —72— to release the lid —70— and permit it to be opened.

60 The cap —45— covering the upper open end of the cage —42— is centrally journalled by anti-friction bearings —76— upon a suitable supporting stud —77— on the underside of the lid —70— so that when frictionally engaged with the upper end of the cage it will rotate freely therewith and will also serve 65 to hold the cage against excessive vibration in case the clothes therein should be slightly heavier on one side than on the other while the cage is being rotated at high speed.

65 The upright perforated walls of the cage —42— are arranged in sufficiently spaced relation to the inclosing walls of the vat —7— to permit the washing or rinsing fluid to be thrown by centrifugal force from the clothes through the perforated side walls of the cage 70 and into the surrounding portions of the vat as the cage is rotated, the gear ratio of the driving mechanism for the cage being such as to rotate said cage at a sufficiently high speed to expel practically all of the moisture 75 from the clothes by centrifugal force so that after a comparatively brief period of operation the clothes are practically dry and more or less fluffy ready for smoothing by a suitable ironing mechanism.

80 Suitable means is also provided for assisting this centrifugal drying of the clothes during the rotation of the cage and for this purpose the lid —70— is provided with a circumferential series of openings —78— while the cover plate —45— for the cage —42— is also provided with openings —79— therethrough and a circumferential series of vanes or ribs —80— extending outwardly from the center thereof and preferably on the upper 85 face of the cover —45— and arranged so as to create circulation of air from the top downwardly through the openings —78— and —79— and thence through the clothes in the revolving cage and out through the perforations in the side walls of said cage into the outer container from which it is drawn into and through the pump, it being understood that during such rotation the clothes are thrown with considerable force from the 90

center and against the perforated walls of the cage, leaving more or less air space in and around the axis of the cage and permitting circulation of air therethrough leaving the clothes in a substantially dry fluffy condition.

It will be observed upon reference to Figure 4 that the brake shoe —59— operates directly against the brake surface —57'— of the brake drum —57— to disengage the clutch member —56— from the clutch gear —18— against the action of the retracting spring —58— which serves to retract both the clutch member —56— and brake drum —57— under which conditions the application of the brake simultaneously with the withdrawal of the clutch member —56— will retard and stop the rotation of the shafts —20— and —20'— and cage —42— driven thereby, all of which greatly expedites the centrifugal drying operation and enables both the brake and clutch to be controlled by the same lever —68— which is coaxial with and in proximity to the washer controlling lever —41— as shown in Figure 2 thus permitting both levers to be operated from the same side of the machine.

This proximate coaxial operation of the two levers —41— and —69— also permits the use of coaxial detents —81— and an interposed coiled spring —82— arranged within a socket 30 in the adjacent portion of the frame —67— for engaging in recesses in the adjacent faces of the levers —41— and —68— to frictionally hold them in their different positions of adjustment, the shaft —66— and lever —68— 35 carried thereby having slightly vertical movement against the action of a retracting spring —83— between the hubs of the crank arms —38— and —65— to adjust the engagement of the extension —68'— with the upper face 40 of the lid —70— when the latter is closed and also to assist in frictionally holding the shaft —66— and tubular shaft —39— against accidental displacement from their adjusted positions.

45 *Fluid circulating mechanism*

Suitable means is provided for withdrawing the washing or rinsing fluid from both of the vats —6— and —7— and also for 50 transferring the suds or other fluid from the drier vat to the washing vat and for these purposes the bottom of the washing vat —6— is provided with an outlet nipple —84— to which is connected one end of a valve case 55 —85— having its other end connected by a conduit —86— to the inlet side —87— of a rotary pump —88—, the latter having its impeller —88'— mounted directly upon the driven shaft —15—, the pump casing forming, in this instance, a part of the gear case —16— as shown more clearly in Figures 6 and 7.

The conduit —86— is connected by a branch —89— to an opening —90— in the bottom of the drier vat —7— to form a liquid

tight joint therewith thereby establishing open communication between the interior of the drier vat —7— and inlet —87— of the pump —88—, see Figures 6 and 13.

The inlet opening of the valve case —85— is controlled by a valve —91— which is yieldingly mounted upon a crank arm —92— of a rock shaft —93—, the latter being journaled in one side of the valve case —85— and provided with an external hand lever —94— by which the valve may be opened and closed at will as may be required to retain or to discharge the water in and from the vat —6—.

The outlet side of the pump —8— is connected by conduit —95— and nipple —95'— to a valve chamber —96— in the frame —67—, said valve chamber having branch openings —97— and —97'— leading from opposite sides thereof and controlled by a hollow valve —98— having an external operating member —98'— and a radial opening —99— which may be brought into registration with one or the other of the branch passages —97— or —97'— to vary the direction of flow of water from the valve chamber.

The branch passage —97— is connected by an elbow —100— to an inlet opening in one side of the washing vat —6— near the upper end thereof while the branch passage —97'— is connected to a discharge nozzle —101— adapted to discharge over a water table —102— into a stationary laundry tray —A— or other receptacle.

In Figures 6 and 11 the valve —98— is adjusted to divert the water from the pump into the nozzle —10— but by turning it one-half turn the opening —99— may be registered with the branch —97— to divert the water from the pump back into the washing vat —6—.

The drain board —102— extends under the adjacent end of the frame —67— at the side of the vat —7— opposite the vat —6— and is preferably hinged at —104— to said frame and provided with opposite concentric slots —105— for receiving clamping bolts —106—, Figure 1, by which the drain board may be tilted to different angles to or from a horizontal plane and locked in any position of adjustment as may be required to direct the water discharge from the nozzle —101— into a suitable receptacle as the vat —A—.

110 *Operation*

The clothes to be washed together with a suitable washing fluid forming what may be termed suds, is placed in the vat —6— beneath the cups —8— under which conditions the valve —91— will, of course, be closed to retain the washing fluid in the vat.

The electric motor —12— is then started by the operation of any suitable controlling switch thereby operating the pump —88—, gear —18—, its pinion —19— and gear —21—.

Throwing the clutch gear —21— into engagement with the clutch member —23— will cause the operation of the lever —27— and plunger —10— carrying the cups —8— for washing the clothes in the vat by alternate pressure and suction as the cups are reciprocated vertically into and out of engagement with the clothes.

As soon as the clothes are properly washed 10 in the vat —6— they may be withdrawn therefrom by hand across the frame —67— and into the cage —42— which has been previously opened for such purpose by opening the lid —70— carrying the rotary cover 15 —45—.

When a sufficient quantity of the previously washed clothes are placed within the revolute cage —42— substantially filling the same, the lid —70— with the cover plate 20 —45— thereon are closed and locked in their closed position with the cover plate —45— frictionally engaged with the upper edge of the cage —42— to rotate therewith, it being understood that the lid —70— will then be 25 firmly held against rotary movement.

The lever —68— and its rock shaft —66— are then turned in the proper direction for releasing the brake shoe —59— and simultaneously engaging the clutch —56— with the 30 clutch gear —18— for transmitting rotary motion from said gear to the shaft —20— and thence through the shaft —20'— and upward shaft —50— to the cage —42— which with the wet clothes therein is driven at relatively high speed to expel practically all of the moisture from the clothes through the 35 perforated walls of the cage and into the vat —7—.

As previously stated, the lower end of the 40 vat is in open communication with the inlet side of the pump —88— through the pipe —89— and owing to the continued operation of the pump —88— the washing fluid accumulating in the vat —7— will be withdrawn therefrom and forced through the pipe 45 —95— into the valve chamber —96— and by adjusting the valve —98— to the position shown in Figures 6 and 11 the washing fluid withdrawn from the vat —7— will be forced 50 outwardly through the passage —97'— and nozzle —101— into one or the other of the laundry trays —A— or into any other suitable receptacle or waste pipe.

Or, if it is desired to withdraw the washing fluid from the vat —6— it may be accomplished by simply opening the valve —91— and allowing the fluid in the vat to pass through the conduit —86— into the inlet side of the pump —88— from which it will be 55 expelled through the pipe —95— into the valve chamber and thence out through the passage —97'— and nozzle —101—.

On the other hand, assuming that it is desired to return the suds water accumulating 60 in the vat —7— and that the valve —91— is

closed, the valve —98— may be reversed to cut off communication between the conduit —95— and branch —97'— and to open communication between said conduit and the branch —97— thus permitting the water to be thrown directly from the drying vat —7— and discharged into the upper portion of the washing vat —6— thus permitting the reuse of the same suds as long as may be desired without varying the amount of water in the washing vat and at the same time maintaining a continuous withdrawal of the fluid from the clothes in the drying vat.

It will be evident from the foregoing description that as soon as the previously washed clothes have been transferred from the washing vat —6— to the drier cage —42— and during the centrifugal drying operation an additional batch of soiled clothes may be placed in the washing vat and operated upon by the washing mechanism without disturbing the operation of the drier cage, all of which greatly increases the output of the machine and effects a complete washing and drying of the clothes with the expenditure of a minimum amount of labor and expense and without liability of injuring the finest of fabrics or mutilation of any parts thereof and at the same time permitting either mechanism to be operated independently of the other or simultaneously as may be required.

We claim:

1. In a high speed rotary extractor mechanism, a vat, a clothes container positioned in the vat, driving mechanism below the vat for rotating the clothes container and including a clutch mechanism for making and breaking the driving connection, a rock shaft extending vertically at one side of the vat and connected to said clutch mechanism below the vat, a cover for the vat, a member secured to the vertical shaft and turning therewith as the clutch is moved to operative and inoperative position, said member being disposed in such relation with respect to the rock shaft that it is moved over the cover to prevent opening of the cover when the clutch is moved in the operative position by rocking of said shaft and so that the member is disposed at one side of the cover when the clutch member is moved to inoperative position by reverse rocking of said shaft, said member constituting a handle for rocking said shaft, and additional means actuated by the rocking of said shaft in the direction to render the clutch inoperative to rapidly reduce the speed of rotation of the container.

2. In a high speed rotary extractor mechanism, a vat, a clothes container positioned in the vat, driving mechanism below the vat for rotating the clothes container and including a clutch mechanism for making and breaking the driving connection, a rock shaft extending vertically at one side of the vat and connected to said clutch mechanism below the

vat, a cover for the vat, a member secured to the vertical shaft and turning therewith as the clutch is moved to operative and inoperative position, said member being disposed in such relation with respect to the rock shaft that it is moved over the cover to prevent opening of the cover when the clutch is moved in the operative position by rocking of said shaft, and so that the member is disposed at one side of the cover when the clutch member is moved to inoperative position by reverse rocking of said shaft, an additional means actuated by the rocking of said shaft in the direction to render the clutch inoperative to rapidly reduce the speed of rotation of the container.

In witness whereof we have hereunto set our hands this 11th day of January, 1928.

JABEZ C. NELSON.

PETER E. GELDHOF.
